FRAME AND SASH CONSTRUCTION

Arthur E. Stiefvater, Happy Valley, Lafayette, Calif., assignor to Kawneer Company, Niles, Mich., a corporation of Delaware

Application June 29, 1955, Serial No. 518,847

11 Claims. (Cl. 189—75)

The present invention relates to a frame and sash construction and has for its primary object the provision of a new and improved split tube type of frame structure for use on door jaams, transom bars, mullions and the like.

Another object of the present invention is the provision of a new and improved split frame and sash construction including complementary frame members constructed to provide a dove tail type of groove when assembled and which are adapted to be secured in assembled relation by a plurality of special headed screws cooperatively associated with the groove defining structure to hold glass panel retaining stops or glazing strips.

In brief, the frame and sash construction of the present invention includes a split tubular frame comprising complementary members having inset overlapping inner and outer portions at least at one and preferably at opposite sides and each of which has an inset groove which may be beveled, adjacent each of the two inset portions. The complementary members are held in assembled relation by a plurality of screws passing through the overlapping portions. The screws have enlarged head portions overlaying the outer inset portions and defining inset groove-like securing means for the reception of a glass retaining stop. A pane of glass is located in a plane passing between a set of beveled grooves and in the plane of the screwheads. The pane of glass is held in place by glass retaining stops each having outwardly extending opposed feet portions, one of which is retained in the groove-like securing means provided by the screwheads and the other in an opposed inset groove in the frame member.

Other objects and advantages of the present invention will become apparent from the ensuing description of an illustrative embodiment thereof, in the course of which reference is had to the accompanying drawings, in which:

Fig. 1 is a fragmentary perspective view illustrating the combined frame and sash construction of the present invention;

Fig. 2 is a fragmentary horizontal cross sectional view of an installation corresponding to that shown in Fig. 1;

Fig. 3 is a transverse cross sectional view of a tubular frame member assembled in accordance with the present invention;

Fig. 4 is a perspective view of one of a number of spring clips which may be used resiliently to support a pane of glass between adjacent stops;

Fig. 5 is an elevational view of one of the special headed screws;

Figs. 6, 7 and 8 are a series of fragmentary vertical cross sectional views illustrating the mode of installation;

Fig. 9 is a view similar to that of Fig. 3, but on a reduced scale, of a modified form of tubular frame construction; and

Fig. 10 is a fragmentary horizontal cross sectional view of a further modification of the invention.

Referring now to the drawings, and first to Figs. 1, 2 and 3, the frame and sash construction of the present invention includes a tubular frame indicated as a whole

2

by the reference character 10 and illustrated best in Fig. 3. The tubular frame is of the split type and includes complementary frame members 12 and 14 having inset overlapping inner and outer portions 12-1 and 12-2 and 14-1 and 14-2, respectively. The complementary frame members are secured in assembled relation by special headed screws indicated generally by the reference characters 16 passing through the overlapping portions of the complementary frame members. Each of the frame members includes an inset groove, which may be beveled, as shown, and preferably adjacent each of its inset portions. Thus, the frame member 12 is provided with an inset beveled groove 12-3 adjacent its inner inset portion 12-1 and a somewhat shallower inset beveled groove 12-4 adjacent the inset portion 12-2. In like manner, the frame member 14 is provided with the inset beveled grooves 14-3 and 14-4. When assembled, the resulting bevels are of like height.

The special headed screws 16 are provided with enlarged head portions 18 overlaying the outer inset portions of the complementary frame members. The screws are provided with threaded ends 20 threaded into at least the undermost one of the overlapping portions. They also are provided with the enlarged (relative to the threaded portions) neck portions 22 which abut against the outer inset portions and thus space the enlarged heads somewhat from the frame members, thereby to provide what might be considered opposed grooves at the opposite sides of the screws and thus located in opposed relation to the grooves in the channel members. These grooves provided by the special headed screws are indicated by the reference characters 24 and 26, the former of which face the shallower beveled grooves and the latter of which face the deeper grooves.

A pane of glass may be located between each set of beveled grooves 12-3 and 12-4 and 14-3 and 14-4 as has been illustrated in connection with the pane of glass 30 in Figs. 1, 6, 7 and 8. The glass may be supported at its bottom edge by supporting blocks, not shown, in conventional manner. The glass is actually supported in the plane of the screws and it is retained in place by glass holding stops, indicated by the reference characters 32 and 34, which are supported in the grooves provided by the special headed screws and in the frame members.

The stops 32 and 34 may be and are illustrated as being identical in construction. Each includes an upper horizontal part 36 and the spaced apart dependent leg portions 38 and 40, the former of which terminates in what might be considered a foot portion 42 and the latter in a foot portion 44, which portions are respectively received and retained in the grooves provided in the frame members and by the headed screws. Generally, it is preferred that the glass actually be retained in place by the glazing springs which may be of the form illustrated in Fig. 4 and indicated by the reference character 46 which are retained between the glass panel and the legs 40 of the stops and underneath the projecting lips 48. Also, the stops may be somewhat resilient, or they may be solid, if desired.

A typical mode of installation is illustrated in Figs. 6, 7 and 8. Fig. 6 illustrates a portion of the tubular frame 10 formed of the complementary members 12 and 14 which are held in assembled relation by the screws 16. In the first step of the installation, one of the stops, such as the stop 30, is placed with its legs 38 and 40 to bring the foot portions 42 and 44 into locking relationship with the grooves 12-4 and 24 in the frame and under the special headed screws, respectively. The glass pane or panel is set against the stop 32 which is now a substantially fixed stop. Wedges 50 are then inserted between the foot 44 and the special headed screws securely to hold the stop 32 in place. The other stop 34 is then moved into place

after the manner illustrated in Fig. 7, the distance between the feet being such as to enable the stops to be located in place by a sort of a rocking or back and forth movement to get the opposed feet into the associated grooves. Then the glazing springs 46 are placed in between the glass and the stops under the lips 48 at the upper and inner sides of the stops. Finally, with the springs in place the glass panel is centered and puttied thereby to provide a completed frame and sash construction.

The present invention is adapted particularly for split tube frame constructions, but it may be used advantageously with integral tubular frames as illustrated in Fig. 9. In this figure there is illustrated an integral tubular frame 50 provided with the inset grooves 52 and 54 on one side of the groove and 56 and 58 on the other. Between the grooves are located the special headed screws 60 for the reception of the glass holding stops.

Fig. 10 of the drawings discloses an additional embodiment of the invention which obviates the need for wedges, such as the elements 50, by firmly securing one of the stop members to the frame construction. More particularly, the sash and frame construction 70 comprises a split frame including a pair of complementary frame members 72 and 74 which are similar to the frame members 12 and 14. These frame members are secured together in an overlapping position by a plurality of screws 76 having enlarged head portions 78. When the frame members 72 and 74 are secured in an overlapping position by the screws 76, a pair of inset beveled grooves 74-1 and 72-1 are provided for receiving and retaining a pair of pane stop members.

To secure a pane 80 of glass in an adjusted position relative to the construction 70, a pair of stops 82 and 84 are provided. The stop 82 is rigidly secured to the assembled frame members 72 and 74, and the stop 84 is detachably retained on these assembled members to secure the pane 80. More particularly, the stop 82, which is somewhat similar in configuration to the stops 32 and 34, includes an outwardly extending foot portion 82-1 which is adapted to be received within the groove 74-1. This stop is also provided with an oppositely directed foot portion 82-2 which is rigidly secured to the assembled frame members by clamping engagement with the enlarged head portions 78 of the screws 76.

The stop member 84, which is not rigidly secured to the assembled frame members but which is capable of being moved into a position in which it is retained thereon, includes a first foot portion 84-1 which is received within the inset groove 72-1 formed in the frame member 72. The stop 84 is also provided with a second oppositely positioned foot portion 84-2 having an inclined upper surface 84-3 which is adapted to be received within the groove-like securing means defined by the enlarged heads 78 of the screws 76.

To install the pane 80 in the sash construction 70, the frame members 72 and 74 are moved into an overlapping position, and the fixed or secured stop member 82 is positioned on the assembled frame members with the foot portion 82-1 received within the inset groove 74-1. Thereafter, the screws 76 are threaded into the overlapped frame members and turned down so that the enlarged head portions 78 thereof engage and secure the foot portion 82-2 of the fixed stop member to the assembled frame members 72 and 74 in addition to securing these two members together to form a unitary frame construction. The pane of glass 80 is then placed adjacent the rigid stop 82, and the stop member 84 is assembled on the frame construction by placing the foot portion 84-1 within the groove 72-1 and by inserting the foot portion 84-1 beneath the enlarged heads 78 of the screws 76, the inclined surface 84-3 facilitating the insertion thereof. Thereafter, glazing springs may be interposed between the pane 80 and the stops 82 and 84, and a suitable glazing compound 86 is inserted therebetween so as to provide a completed frame and sash construction.

While the present invention has been described in connected with certain illustrative embodiments thereof, it should be understood that these details are not intended to be limitative of the invention except insofar as set forth in the accompanying claims.

Having thus described my invention, what is claimed as new and desired to be secured by United States Letters Patent is:

1. A frame and sash construction including, in combination, a split tubular frame including complementary members having inset overlapping inner and outer portions at opposite sides and each having an inset groove adjacent each of its inset portions, a plurality of screws passing through said overlapping portions for securing said members in assembled relation, said screws having enlarged head portions overlapping the outer inset portions, said heads defining inset groove-like securing means for the reception of a glass stop, a pane of glass in the plane of each set of said grooves on said members and the screwheads, and glass holding stops each having outwardly extending opposed feet portions, one of which is retained in the groove-like securing means provided by the screwheads and the other in an opposed inset groove.

2. A frame and sash construction including, in combination, a split tubular frame including complementary members having inset overlapping inner and outer portions at opposite sides and each having an inset groove adjacent each of its inset portions, a plurality of screws passing through said overlapping portions for securing said members in assembled relation, said screws having enlarged head portions overlapping the outer inset portions, said heads defining inset groove-like securing means for the reception of a glass stop, a pane of glass in the plane of each set of said grooves on said members and of said screwheads, glass holding stops each having outwardly extending opposed feet portions, one of which is located under the groove-like securing means provided by the screwheads and the other in an opposed inset groove, wedges between the screwheads and the foot portion of the stops at one side of the glass panes, and spring means at both sides of each glass pane between the pane and adjacent side of the associated stop.

3. A frame and sash construction including, in combination, a split tubular frame including a pair of members having inset overlapping inner and outer portions and each having an inset groove adjacent its inset portion, a plurality of screws passing through said overlapping portions for securing said members in assembled relation, said screws having enlarged head portions overlaying the outer inset portion, said heads defining inset groove-like securing means for the reception of a glass stop, a pane of glass in the plane of said beveled grooves on said members and the screwheads, and glass holding stops each having outwardly extending opposed feet portions, one of which is retained in the groove-like securing means provided by the screwheads and the other in an opposed inset groove.

4. A frame and sash construction including, in combination, a tubular frame having spaced apart inset grooves on opposite sides, a plurality of screws mounted in the space between each set of grooves, said screws having enlarged head portions overlaying the frame structure, said heads defining inset groove-like securing means cooperating with said grooves for the reception of a glass stop, a pane of glass in the plane of said screwheads, and pane holding stops each having outwardly extending opposed feet portions, one of which is retained in the groove-like securing means provided by the screwheads and the other in an opposed inset groove.

5. A frame and sash construction including, in combination, a frame structure having spaced apart inset grooves, a plurality of screws mounted in spaced apart relation in the space between said grooves, said screws having enlarged head portions overlaying the frame structure, said heads defining inset groove-like securing

means cooperating with said grooves for the reception of a glass stop, a pane of glass in the plane of said screwheads, and glass holding stops each having outwardly extending opposed feet portions, one of which is retained in the groove-like securing means provided by the screwheads and the other in an inset groove.

6. A frame and sash construction including, in combination, a split tubular frame including complementary members having inset overlapping inner and outer portions at opposite sides and each having an inset groove adjacent each of its inset portions, a plurality of screws passing through said overlapping portions for securing said members in assembled relation, said screws having enlarged head portions overlaying the outer inset portion and defining inset groove-like securing means cooperating with said grooves for the retention of glass stops.

7. A frame and sash construction including, in combination, a tubular frame having spaced apart inset grooves on opposite sides, a plurality of spaced apart screws mounted in said space between each set of said grooves, said screws having enlarged head portions overlaying the frame structure and defining inset groove-like securing means cooperating with said grooves for the reception of glass stops.

8. A frame and sash construction including, in combination, a tubular frame having spaced apart inset grooves, a plurality of screws mounted in the space between said grooves, said screws having enlarged head portions overlaying the frame structure and defining inset groove-like securing means cooperating with said grooves for the reception of glass stops.

9. A frame and sash construction including, in combination a frame having spaced apart inset grooves on opposite sides, a plurality of screws mounted in the space

35

between each set of grooves, said screws having enlarged head portions overlapping the frame structure, said heads defining groove-like securing means cooperating with said grooves for the reception of glass pane stops, a pane of glass in the plane of said screwheads, and a pair of pane holding stops each having outwardly extending opposed feet portions, one of said stops having the feet portions thereof rigidly secured by said inset groove and said screwheads, the other of said stops being removably retained by engagement of the feet portions thereof with said inset groove and the heads of said screws.

10. A frame and sash construction comprising a split frame including a pair of members having inset overlapping inner and outer portions and each having an inset groove adjacent its inset portion, a plurality of screws passing through said overlapping portions for securing said members in an assembled relation, said screws having enlarged head portions to define a groove-like securing means, a pane of glass in the plane of said head portions, a first stop member having a first foot portion retained by one of said inset grooves and a second opposed foot portion rigidly secured to said split frame by the head portions of said screws, and a second stop member having a first foot portion retained by another of said inset grooves and a second opposite foot portion slidably received within said groove-like securing means.

11. The construction defined by claim 10 in which the second foot portion of the second stop member is inclined from the frame toward the head portions of the screws.
